Atlys.

UNITED STATES PATENT OFFICE

DANIEL E. HENNESSY, OF CAMBRIDGE, MASSACHUSETTS, ASSIGNOR TO LEWIS-SHEPARD COMPANY, OF WATERTOWN, MASSACHUSETTS, A CORPORATION OF MASSACHUSETTS

PLATFORM

Application filed January 18, 1927. Serial No. 161,856.

This invention relates to improvements in portable platforms which are adapted to be transported from place to place with the load thereupon, by elevating trucks, and the particular object of the invention is to provide a platform having end frames in the form of adjustable channels which can be made to fit upon the ends of the floor members of different thicknesses and which end frames will serve also as a protection to the ends of the floor members.

A further object of the invention is to provide a platform in which the legs extend longitudinally of the floor members for the purpose of causing the introduction of the elevating trucks beneath the ends of the platform which are bound by the end frames instead of being introduced beneath the platform in a direction transversely of the length of the floor members as is usual in the general use of platforms of this type.

A preferred embodiment of the invention is illustrated in the accompanying drawing in which:

Fig. 1 is a side elevation of a platform containing the invention;

Fig. 2 is a plan view of the same;

Fig. 3 is a detail view in vertical section illustrating the different arrangement of the angle bars forming the end frames;

Fig. 4 is a detail view of the preferred arrangement of the angle bars to form the end frame; and

Fig. 5 is a side elevation of a platform embodying the invention, the central portion of the platform being broken away.

The platform comprises a series of floor members 1 with end frames formed of angle bars embracing the ends of the floor members and clamping the same therebetween. In the construction illustrated in Fig. 1 the horizontal flanges 2 of the upper angle bars engage the upper face of the ends of the floor members while the vertical flanges 3 thereof engage the ends of the floor members. The horizontal flanges 4 of the lower angle bars engage the under face of the ends of the floor members while the vertical flanges 5 thereof engage the ends of the floor members and are in the same plane with the vertical

flanges 3 of the upper angle bars. Suitable means such as bolts 6 extend through the horizontal flanges of the upper and lower angle bars and also desirably through the leg members serve to clamp the angle bars firmly upon the ends of the floor members and also to secure the legs to the side frames. By reason of this construction end frames can be readily constructed to fit floor members, such as planks, of any desired thickness, and any looseness which may occur by shrinkage of the floor members, wear or otherwise, may be readily taken up by setting up the nuts upon the bolts.

In the preferred form of construction the legs 7 are U-shaped with horizontal flanges 8 and 9 at the upper ends of the leg members. The flange 8 desirably is engaged by the bolt which clamps the angle bars upon the ends of the floor members. The legs extend longitudinally of the floor members and the flanges 9 thereof are connected to the floor members by bolts 10 the heads of which desirably are countersunk in suitable recesses in the faces of the floor members. By thus positioning the legs longitudinally of the floor members a platform construction is provided which differs from usual types of platforms in which the legs are arranged beneath the metallic side frames and presents a platform under which the elevating trucks will be naturally introduced in longitudinal direction of the floor members.

By thus connecting the inner end of the legs at a distance from the end of the platform floor members to which the other end of the leg is secured through the metallic side members, a much more rigid construction is provided than in the usual construction in which both ends of the legs are secured to the end frame members, because the legs extend in a direction in which force is generally applied to the platform. Furthermore, the remote anchorage of the inner end of the legs avoids the likelihood of causing the bolts to split out the ends of the platform. This is especially true where no metallic girders are provided to connect the end frames of the platform.

The angle bar end frames will therefore

protect the ends of the platform from any injury which might occur by the careless backing of the trucks beneath the platform. The platform above described is of very simple construction and can be made of standard materials at a minimum cost.

The angle bars which form the end frames may be of any suitable size or construction.

A modified form of end frame is illustrated in Fig. 3 which comprises an upper angle bar having a horizontal flange 11 and a vertical flange 12 and a lower angle bar having a horizontal flange 13 and a vertical flange 14 which is overlapped by the vertical flange 15 12 and upper angle bar. The platform members 1 are clamped between horizontal flanges 11 and 13. It will be noted that the relative positions of the angle bars are such as to provide an adjustable channel to receive the ends 20 of the floor members so that floor members of any desired width may be introduced into such channel and firmly clamped therein by bolts 15 which pass through the horizontal flanges 11 and 12 of the upper and lower angle 25 bars and also desirably through the horizontal flanges 8 of a leg 7 of the type illustrated in Fig. 1, the nut 16 upon the bolt 15 being adapted when set up to clamp the upper and lower angle bars together with the ends of 30 the floor members between the horizontal flanges of the angle bars.

In the preferred construction illustrated in Fig. 4 the upper angle bars comprise horizontal flanges 17 which engage the upper 35 faces of the floor members 1 and vertical flanges 18 which engage the ends of the floor members; the lower angle bars comprise horizontal flanges 19 which engage the under faces of the floor members and vertical flanges 20 which overlap the vertical flanges 18 of the 40 upper angle bars.

The horizontal flanges 8 of the U-shaped legs engage the horizontal flanges 19 of the lower angle bars and bolts 20 serve to secure 45 the angle bars and flanges of the legs together and also to clamp the ends of the floor members between the horizontal flanges of the angle bars as above described.

In the construction illustrated in Fig. 4 the 50 overlapping vertical flanges present a double thickness of metal to protect the ends of the floor members.

It will be understood that the embodiments 55 of the invention disclosed herein are of an illustrative character and that various changes in form, construction and arrangement of parts may be made within the spirit and scope of the following claims.

Having thus described the invention, what 60 is claimed as new, and desired to be secured by Letters Patent, is:

1. A platform having a series of floor members, end frames therefor comprising upper and lower metallic angle bars engaging the 65 ends and the upper and lower faces of the

ends of said floor members thereby providing metal-bound platform ends, means for clamping said angle bars with the floor members therebetween and legs extending lengthwise of the floor members connected at one end to the lower angle bars by said clamping means and connected at the other end to the floor members at a distance from said end, whereby the legs form braces to resist lateral movement of said angle bars and prevent the bolts from splitting out of the ends of the floor members.

2. A platform having a series of floor members, end frames therefor comprising upper and lower metallic angle bars having overlapping vertical flanges and embracing the ends of said floor members, bolts securing said angle bars together with the ends of the floor members therebetween, thereby forming adjustable channels fitting the ends of said floor members and U-shaped legs extending longitudinally of said floor members having at their upper ends horizontal flanges the outer of which are secured to the end frames by said bolts and the inner flanges of which are secured to said floor members at a distance from the end frames, whereby the legs form braces to resist lateral movement of said angle bars and prevent the bolts from splitting out of the ends of the floor members.

3. A platform having a series of floor members, end frames therefor comprising reversely arranged upper and lower metallic angle bars having overlapping flanges and embracing the ends of the floor members thereby providing a double thickness of metal at the ends of said floor members, bolts securing said angle bars together with the ends of the floor members therebetween thereby forming adjustable channels fitting the ends of said floor members, and U-shaped legs extending longitudinally of said floor members having at their upper ends horizontal flanges the outer of which underlie said end frames, bolts extending through said end frames and said flanges, and bolts connecting the inner flanges of said legs to said floor members at a distance from the end frames, whereby the legs form braces to resist lateral movement of said angle bars and prevent the bolts from splitting out of the ends of the floor members.

In testimony whereof, I have signed my name to this specification.

DANIEL E. HENNESSY.
